(57) **CLAIM**

The ornamental design for a boat dock fender bumper, as shown and described.

DESCRIPTION

FIG. 1 is a rear, bottom, right perspective view of a boat dock fender bumper, showing my new design;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, top, right perspective view thereof, for clarity of illustration; and,

FIG. 9 is another left perspective view thereof, for clarity of illustration.

1 Claim, 9 Drawing Sheets
